UNITED STATES PATENT OFFICE.

ADOLPH ROSZKOWSKI, OF PETROGRAD, RUSSIA.

PNEUMATIC HYDROSTATIC SYSTEM.

1,240,373.

Specification of Letters Patent. Patented Sept. 18, 1917.

Application filed April 17, 1912, Serial No. 691,399. Renewed December 11, 1916. Serial No. 136,370.

To all whom it may concern:

Be it known that I, ADOLPH ROSZKOWSKI, a subject of the Czar of Russia, and residing at Petrograd, Russia, have invented certain new and useful Improvements in Pneumatic Hydrostatic Systems, of which the following is a specification.

My invention relates to a pneumatic water supply system, and a primary object is 10 to provide a system comprising reservoirs at the supply stations directly connected to the pressure mains, said reservoirs having water spaces connected with the pressure mains led from the pump and having air 15 spaces connected one with another by a common pipe, in which automatic outwardly closing valves are provided just beyond the pipe connections to the reservoirs, in order that when water is drawn off at one station 20 the air is prevented from flowing out of the contiguous reservoirs.

One embodiment of my invention is diagrammatically illustrated by way of example in the accompanying drawing.

25 Referring to the drawing, 1 designates the pump, 2 the suction pipe, and 3 the pressure pipe.

In the illustrative embodiment three supply stations designated I, II and III are 30 shown. At each of these stations there is a reservoir 4, to which the pressure main 3 is connected. At station I there is also an air chamber 5 which serves as an auxiliary to the air space in the reservoir 4. The water 35 supply pipes 6 are also connected to the pressure main 3, and water is supplied by opening the cocks 7.

At station I the reservoir 4 and the air chamber 5 are connected by a pipe 8 which 40 opens into the reservoir at 10. An automatic valve 11 is located between the reservoir 4 and the pressure main 3. The air spaces of the reservoirs of the supply stations I, II, III are connected by means of the 45 pipe 9, in which an automatic outwardly closing valve 12 is inserted just beyond the connection of the pipe to each reservoir. This pipe 9 is also provided with a closed air supply-opening at 13, which is capable 50 of being opened for admitting compressed air when insufficient air is present.

The pipe 9, instead of being connected to the pipe 8 as at station I, may be connected to the chamber 5, as shown at station III.

55 My improved pneumatic water supply system operates as follows:

The reservoirs at the various stations are first filled by the hydraulic pump 1 to such an extent that there is sufficient in each for the day's requirements. 60

Now if the cock 7 at station I, for example, is opened, the water flowing outward through the supply pipe 6 principally comes from the reservoir at this station. Although the water spaces of the reservoirs are connected together by the pipe 3, under the circumstances the supply of water will chiefly come from the reservoir at station I. Consequently, the air in this reservoir will expand and the pressure at this station will be 65 reduced more than at the other supply stations II and III. There is therefore a tendency for air to flow through the piping 9 from the reservoirs at stations II and III into that of station I. Pressure is thus exerted on the valve 12 which can only open inwardly and this valve is closed owing to the greater pressure prevailing on its inner side. There is a growing difference of pressure at the station I as compared with that 70 at the other stations when water is drawn off from this station, and this difference of pressure causes the water to flow from the other stations through the pipe 3 toward the supply station I. As soon as water ceases 75 to be drawn off the water at all the stations comes to the same level, because the pressure differences are gradually eliminated. The valves 12 are released and the whole 80 system returns to its original condition. 90

The valves 12 close outward as stated; under the normal condition of the installation they are open, whereby easy access to the pipe 9 is given to the air. This occurs 95 when the pressure exerted by the air is not sufficiently great to close the valve 12, but is sufficient to bring about an equality in the quantity of air within the apparatus at each station.

In addition, the valve 12 prevents air escaping from the apparatus in case of injury to the pipe 9. The valve 12 operates in the same manner when the air is discharged at one of the stations. 100

This arrangement of water supply stations on the plots of land to be provided with water has the following advantages:

1. The erection of a receiving reservoir, which appeared to be unavoidable in such plants known heretofore, is here dispensed with. The result is that the supply pipes 110 6 and the reservoirs 4 can be directly con-

nected to the pressure mains 3. This again has the advantage that the size of the main 3 can be calculated according to the velocity of the water delivered by the pump which 5 results in a smaller diameter of pipe. Only the short portions of this pipe which are between the reservoirs and the discharge places must be designed corresponding to the velocity of the discharged water.

10 2. As the chief discharge points are principally fed from contiguous reservoirs, water can be simultaneously drawn off at different points without the velocity of the discharged water being reduced on that account. This 15 however is also the case when the water is supplied from one central reservoir.

15 3. The removal of a discharge point farther from the pump has no influence on the 20 velocity of the discharged water, because a reservoir may be erected in the vicinity of this point.

20 4. The result of installing the reservoirs 4 near the discharge points is that the plant is protected from hydraulic shocks, which 25 could otherwise occur on the cock 7 being closed, because the force of such shocks is reduced owing to the very small quantity of water present between the reservoir and the discharge point.

30 5. The readjustment of the water to the same level in the different reservoirs during and after the discharge takes place in a very short time, as this equalization is brought about not only by the pressure of the water, 35 but also by the difference in air pressure. This circumstance allows water to be still discharged at one of the supply stations, even when the reservoir there has already been emptied, because the inflow from the 40 other reservoirs takes place sufficiently quickly.

40 6. Injury to the pipe 9 or the discharge of

the air from one of the reservoirs does not put the whole system out of operation.

7. Finally, a further advantage of the new 45 system is that the reservoirs under pressure can be erected at various points in the district to be provided with water. This improvement is due to the provision of the valves 12.

50 I claim:—

1. A pneumatic water supply system comprising a plurality of tanks spaced apart, a common water supply pipe, independent connections between said pipe and tanks, valved discharge pipes connected with said common water supply pipe adjacent to said tanks respectively, a common air supply pipe, pipes severally connecting said tanks with said common air supply pipe, and automatic check valves for the air connections of the several tanks, said check valves opening 55 toward said tanks.

2. A pneumatic water supply system comprising a plurality of water tanks spaced apart, a plurality of air tanks severally disposed adjacent to said water tanks, a common water supply pipe, independent connections between said common supply pipe and said water tanks, valved discharge pipes connected with said common water pipe adjacent to said water tanks, pipes connecting said water and air tanks in pairs, a common air supply pipe, independent connections between said air pipe and said air tanks, and 60 check valves for said connections opening toward said air tanks.

70 In testimony, that I claim the foregoing as my invention; I have signed my name in presence of two subscribing witnesses.

75 ADOLPH ROSZKOWSKI.
